UNITED STATES PATENT OFFICE

HARRY HALLAM, OF LEICESTER, ENGLAND, ASSIGNOR TO UNITED SHOE MACHINERY CORPORATION, OF PATERSON, NEW JERSEY, A CORPORATION OF NEW JERSEY

TREE OR TREE FOOT

Application filed November 4, 1931, Serial No. 572,984, and in Great Britain November 27, 1930.

This invention relates to trees or tree feet suitable for use in treeing boots and shoes and is herein illustrated as embodied in tree feet adapted for use in treeing machines of the type disclosed in United States Letters Patent No. 1,797,020, granted March 17, 1931, on application of Read et al.

Treeing machines of the type referred to, like other machines for use in performing treeing operations on boots or shoes (hereinafter for convenience referred to simply as shoes), are provided with treeing forms or "feet" on which the shoes are supported while cleaning, polishing and ironing operations are carried out upon their uppers, the "feet" being expandible in various directions so as fully to fill the shoes after the latter have been placed on them. The tree feet of the patented machine are removable from the machine without deflation and are capable of use for holding shoes in their intended shape for considerable periods, for display or otherwise. When so used, they are commonly termed "trees." Accordingly, the expression "tree" is used hereinafter to cover any device for filling a shoe and intended to bring it to its original lasted shape.

It is desirable that the tree employed to fill a shoe for a treeing operation should as nearly as possible duplicate in its outlines the last on which the particular shoe was made so that ironing operations, for instance, may not impart to the shoe any different shape from that originally intended. Pneumatical- 30 ly expandible or inflatable trees have commonly been provided with pliable, as opposed to resilient, coverings such as leather or relatively soft rubber. This sort of tree is ad- 35 vantageous in that the tree itself does not need to be given the exact shape of the last on which the shoe to be treated was made and is capable of filling completely the shoe, leaving no gaps or unsupported portions.

One important object of the present invention is to provide an improved shoe tree or tree foot for a shoe treeing machine which effectively will retain unchanged, under pressure of expansion to fill a shoe, the exterior 40 contours imparted to the shoe by its last.

This object is attained in the illustrated construction by providing, in accordance with one feature of the invention, a shoe tree having an exterior cover member, which cover member is made of relatively stiff but resil- 55 ient material adapted to fill the shoe or even to distend the shoe very slightly when it is pressed against the interior of the shoe as by reason of inflation of a body member therein and at the same time to retain substantially 60 unchanged the exterior contour of the shoe imparted during the lasting operation. The illustrated resilient cover member or shell substantially surrounds the sides of the body member and is arranged, in accordance with 65 another feature of the invention, particularly to facilitate extension laterally of the shoe, thereby to fill at least the forepart of the shoe. The shell may advantageously be constructed of comparatively hard rubber which, 70 when vulcanized, is resilient and not merely pliable. For some grades of work the shell may satisfactorily be constructed of celluloid or fiberboard.

In accordance with still another feature 75 of the invention, the illustrated shoe tree has a shoe-upper-engaging surface composed of material, such as hard rubber, which is only slightly distortable by inflation and is ar- 80 ranged to engage substantially the whole of the interior of the shoe upper above the sole of the shoe, and also has a shoe bottom engaging surface which is composed of material, such as soft rubber, which is readily distortable by inflation and hence is also capable of lat- 85 eral expansion. As illustrated, this upper- 90 engaging surface is constructed of a stiff, re- silient material such as hard rubber capable of lateral deflection upon expansion of the sole-engaging surface, thereby to distend the shoe laterally while retaining substantially the same exterior contour which the shoe had before the last was removed.

Still another feature of the invention re- 95 lates to the provision upon the resilient, shell- like covering of a peripheral flange under- lying part of the bottom surface of the body member. As illustrated, this flange is wider around the extreme toe end of the shoe than it is along the sides.

The above and other objects and features of the invention will become apparent from a consideration of the following description with reference to the accompanying drawing of convenient constructions of trees according to the invention and of the mode of use thereof.

In the drawing,

Fig. 1 is a side view of a pneumatically 10 expandable tree for a woman's shoe;

Fig. 2 is a plan view of the same inverted;

Fig. 3 shows, on a larger scale, a section on the line III—III of Fig. 1; and

Fig. 4 shows on a still larger scale a section 15 on the line IV—IV of Fig. 1.

The illustrated tree is of a type suitable for use in connection with the treeing machine of the Read patent mentioned above, it being capable of ready attachment to said 20 machine for inflation, and detachment from the machine while still in an inflated condition. To this end the tree, as does also the tree foot illustrated in the Read patent, comprises a pneumatically expandable or 25 inflatable body member 10 (Figs. 3 and 4) of rubber or other suitable pliable material and has a cone-shaped ridge member 5 and an outer plate 6 attached thereto by screws 7. This plate 5 is provided with a hole to receive 30 a nipple 8 inserted in which is a sleeve 9 housing a spring-pressed poppet valve 11. On the upper surface of the plate 6 there is a central boss 12 to which there is attached by screws (not shown) a supporting disk 13. 35 By means of this boss 12 and the disk 13 the tree may be readily connected to the treeing machine, as shown in said patent, and the body member 10 inflated. The construction is such that the tree may be removed from 40 the treeing machine while still in an inflated condition.

Over the inflatable body member 10 and the inner plate 5 is fitted a shell or covering 18 of resilient material such, for example, as one 45 of the well-known types of rubber which is comparatively hard and which, when vulcanized, becomes relatively stiff and resilient, and not merely pliable as is the rubber used for the body member 10. Such a rubber shell 50 is generally preferable for women's work instead of celluloid or fiberboard, either of which, however, may be used.

It is desirable in some instances when the shell is made of special rubber, as indicated 55 above, or otherwise when the material of the shell, whatever its nature, requires it, that the upper part of the tree should have a solid instep filling portion. This may be formed, as shown in Figs. 1 and 3, by the inner plate 14 60 which may be made to extend down to the dotted line 32 in Fig. 1 and as shown in Fig. 3 over the upper portion of the inflatable interior 10 and inside the shell 18.

As indicated by Fig. 2, the shell is provided 65 on the sole face of the tree with a flange 20 ex-

tending around the forepart of the tree. This flange is narrower along each side of the forepart than it is at the toe, since where resilient rubber is employed for the shell there will usually be sufficient elasticity in the material to allow some lateral expansion at the toe end though very little expansion at this point can ever be in practice required. The flange 70 serves to hold the flimsy, expandable inner body member in place as the tree is inserted in a shoe and for this reason it is preferable, where the material employed for the shell permits of it, to have a flange 23 of substantial width at the extreme toe end so that there shall not be any tendency for the toe end of the shell to spring off and expose the toe end 75 of the inner body member as the sole surface of the toe of the shell is inserted in the shoe and pushed along in contact with the inner sole surface of the latter.

The sole flange 20 of this shell is of as small a width as is practical along the sides of the forepart in order to reduce friction between the flange and the inner sole surface of the shoe as the tree is expanded after insertion. 80 Where rubber or like material, as opposed for instance to celluloid which has a comparatively hard and frictionless surface, is used for the shell, the use of wide flanges at the forepart sides is preferably avoided as being likely to prevent full and easy expansion of the tree.

As shown in Fig. 4, the edges of the shell where the flanges meet the side walls are 85 made substantially angular, as indicated by 90 the reference numerals 21, so that when expanded the shell may fill the shoe at the feather line snugly. The material of the shell may be first built up and finally scoured 95 off to produce this result.

As indicated in Fig. 2, on the sole surface in the shank of a tree of this construction the edges of the shell approach one another at the points 22, finally meeting at a point 24 well 100 in advance of the heel. In women's work it 105 is not usually necessary for the heel portion of an expandible tree to have more than limited extensibility. The heel end of the shell is made narrower in width than the last 110 on which the shoe was made, as indicated at 115 25 in Fig. 2, and is rounded off at the heel end by blending the lower part of the heel end, as seen at 26 in Fig. 1, into the sole by an easy 120 curve (as is usual with hollow shoe display fillers), both these modifications from the 125 last shape being made to secure easy entrance of the tree into and exit from the shoe.

The main area of the sole face 30 of the inflatable interior is, with the form of shell indicated, exposed and, since the shell usually needs no bottom portion or cross strut, as is usual with hollow display fillers, is free to expand downwardly against the insole surface of a shoe in which the shell is placed.

A resilient shell constructed as above indi-

cated provides a correctly contoured internal support for the entire forepart and shank of particularly ladies' oxfords and does not tend to distort the edges of uppers of such 67 5 shoes or their instep strap if present. Also, the margin of the shell adjacent to the sole affords correctly shaped support for the feather of the upper around the forepart and 70 in the shank of the shoe, an effect not usually 68 10 obtainable with inflatable tree feet of usual type which generally tend to give undue convex curvature to these parts.

In use, the tree thus formed of an inflatable 69 15 interior body member 10 and a resilient shell 15 18 may be inflated and handled exactly as the tree feet described in the Read Patent No. 1,797,020 referred to above. The shell is sufficiently flexible as a whole for its sides to 75 20 spread apart and thus fill a shoe but will provide an external surface all over the upper 25 25 of a shoe fitted upon it which represents substantially exactly the contours of the last which the shell substantially duplicates. The action of distending the inflatable body member produces no substantial alteration in 30 30 the exterior shape of the shell which retains in particular any concave curvatures it possesses. The inflatable body member is free, as before indicated, over practically its whole sole surface to force the shell against the interior of the shoe upper.

In dealing with other classes of shoes, for instance men's work, it may be desirable to employ a more rigid material for the shell 35 35 than the resilient rubber above indicated. Fiberboard or celluloid molded to the shape of an individual last in the manner habitually employed for making shoe display fillers may be employed.

In such an instance the shell will preferably be molded with a part or portions integral with the main body of the shell to form a crown for the shell which may be clamped between inner and outer plates in the same 40 45 way as the rubber referred to above. Viewed from the sole face, a shell of this particular character will preferably have a flange which is very narrow around the toe end of the shell so as to avoid imparting any substantial degree of rigidity against pressure applied laterally to the shell sides either inwardly or outwardly. Also, with a shell of this nature the edges of the shell preferably gradually 50 55 approach one another from the region of the ball line between the forepart and shank portions of the foot until they meet at the heel end, being conveniently joined together round the extreme rear of the heel at a distance about one inch above the heel seat of the corresponding last.

Since the margins of a shell thus made do not meet at the heel end of the shell below the upper part thereof, the interior is enabled 60 65 to expand at the lower portion of the heel

end to force the shell bodily snugly into the forepart of a shoe upon it.

The fitting of resilient shells of the kinds and in the manner above indicated over inflatable foot portions enables usually greater simplicity than heretofore in construction of the inflatable portion to be employed. When inflatable body members have been encased in pliable covers, it has in most instances been found necessary to provide a large number of internal ribs extending across the interior space of the inflatable member in order to preserve as far as might be possible its exterior contours when inflated. When an inflatable body member is housed within a resilient shell in the manner above described, the main requirement remaining for the interior portion is that the sole surface shall not distend too far along its mid line when subjected to internal pressure. The retention of a very few ribs 34, shown as three in Figs. 3 and 4, or even a single internal rib (of material, it being understood, extensible to some degree) is sufficient to secure the result desired. 70 75 80 85 90

In dealing with shoes having uppers of some classes of leather, generally those of light weight and glossy surface, it is desirable to provide a supporting surface, against which the upper may be ironed, of a somewhat yielding character. In such instances the employment of the specially resilient qualities of rubber above indicated will usually provide a surface such as is desired. 95

Having thus described my invention what I claim as new and desire to secure by Letters Patent of the United States is:

1. A pneumatically expandible shoe tree having an inflatable body member and an exterior cover member of relatively stiff resilient material shaped to simulate a shoe upper and having curves and sharp corners like those of the contour of a shoe and adapted, when pressed against the interior of a shoe by inflation of the body member, substantially completely to fill or even temporarily slightly to distend the shoe while retaining substantially unchanged the exterior contour of the shoe imparted by lasting. 100 105 110 115

2. A pneumatically expandible shoe tree comprising an inflatable body member, a resilient shell substantially surrounding the sides of said body member with its edges separated along the bottom thereof and arranged for extension laterally of the shoe thereby to fill completely at least the forepart of a shoe in which the tree is fitted. 120

3. A shoe tree according to claim 2 in which the shell is formed of resilient sheet material such as celluloid. 125

4. A shoe tree according to claim 2 in which the shell is formed of fiberboard.

5. A shoe tree according to claim 2 in which the shell is formed of rubber having greater resiliency and stiffness than the body member. 130

6. A pneumatically expandible shoe tree provided with a shoe-bottom-engaging surface of a material readily distortable by inflation, said shoe tree having a curved top surface, arranged to engage substantially the whole of the interior of a shoe upper above the sole of the shoe, of a material which is only slightly distortable by inflation.

7. A pneumatically expandible shoe tree having a shoe-sole-engaging surface of material which is laterally stretchable upon inflation of the tree and having a surface arranged to engage the interior of a shoe upper above the sole thereof of a stiff, non-stretchable resilient material the lower portion of which are free for lateral deflection on expansion of the sole-engaging surface, thereby to fill the shoe completely laterally while retaining substantially the same exterior contour which the shoe had before the last was removed.

8. A pneumatically expandible shoe tree comprising an inflatable body member and a resilient shell-like covering for said body member, said resilient covering having a peripheral flange underlying part of the bottom surface of the body member and forming sharp angles with the upper surface around the forepart.

9. A pneumatically expandible shoe tree comprising an inflatable body member and a resilient shell-like covering for said body member, said resilient covering having a peripheral flange underlying part of the bottom surface of the body member, said flange being narrower along the sides than it is around the extreme toe end of the tree.

In testimony whereof I have signed my name to this specification.

HARRY HALLAM
